METHOD AND MEANS FOR EYE TREATMENTS

Charles H. Schwaner, Scottsbluff, Nebr.

Application June 13, 1936, Serial No. 85,145

7 Claims. (Cl. 128—25.1)

This invention is directed to a method of and means for providing for eye treatments wherein the conventional spherical lenses, as ordinarily employed by the patient in reading or the like, are used and the treatment perfected while the patient is using such lenses for their ordinary and usual purpose.

It is well known in this particular art to treat the eyes of the patient for certain defects through an increase or decrease of prism power and such results have been attained by the employment of special implements which are adjusted or changed to suit the particular patient's requirements which are ordinarily costly and complicated and 15 requires the attendance of the patient at the office of the optometrist. The costly and complicated nature of these implements materially restricts their use in general practice and at best limits the number of patients who may be treated 20 during working hours, and it is a serious encroachment on the time of the patient in waiting for treatment and in making further visits for additional treatments.

The primary object of the present invention is 25 the provision of an apparatus of simple and comparatively inexpensive character in which the treatment is provided through the use of the spherical lenses peculiar to the patient for ordinary reading or like purposes, and the apparatus 30 as a whole is designed for convenient support upon the head of the patient, permitting the treatments to be carried out while the patient is using the particular lenses giving the treatment for ordinary purposes, such as reading or the like. 35 It is well recognized that the ordinary spherical lenses, when moved to the right or the left of the optical point, increases the prism power, having an increased stimulative effect in one direction and an inhibitory prism effect when moved in the 40 opposite direction. The present invention is designed to take advantage of this well-known condition of spherical lenses, ordinarily employed as eye-glasses, and to utilize, as a method of treatment, a means for moving the lenses when in ordinary position and function for their usual purpose to gain the desired prism power for treatment purposes.

The apparatus employed, therefore, as an illustrative means of carrying out the method involves the provision of a carrier to be removably supported upon the head of the patient, on which carrier ordinary spherical lenses in use by that patient for reading purposes, or lenses similar thereto, are mounted, with means by which the 55 lenses, which when adjusted to the head of the

patient are in position relative to the eyes for all ordinary purposes, are slowly moved laterally toward and from each other while the lenses are being employed by the patient for ordinary reading purposes.

This apparatus will be described in connection with the accompanying drawings, in which:

Figure 1 is a view in elevation of the eye treatment apparatus with the cover plate removed, the movement compensating means being broken out.

Figure 2 is a view in elevation of the slide for accommodating the movements of the patient during treatment.

Figure 3 is a plan view of the apparatus, the cover plate being shown in position.

Figure 4 is a vertical section through one of the slots of the follower plate.

Figure 5 is a view in elevation of the supporting plate.

Figure 6 is a view in elevation of the apparatus with the cover plate in applied position.

Figure 7 is an enlarged section showing the mounting of the parts on the supporting plate.

Figure 8 is a front elevation of a modified form, 25 the cover plate being removed.

Figure 9 is a bottom plan view of the construction shown in Figure 8.

Figure 10 is a section on the line 10—10 of Figure 8.

Figure 11 is an enlarged view in elevation, partly in section, showing the lens adjustment means.

The apparatus comprises a carrier including a head band having a substantially rigid frontal piece 1 to extend across the head of the patient above the eyes, to the ends of which is connected a flexible adjustable preferably elastic strap 2 to fit the rear portion of the head of the patient and hold the carrier in proper position. The carrier includes a plate 3 depending from the frontal piece 1 and formed at appropriate points with openings 4 which of course, when the carrier is in place, register with the eyes of the patient.

Extending transverse the forward face of the plate 3 above the openings 4 is a bar 5 formed with a longitudinal guide channel 6. Rotatably supported above the guide bar 5 about centrally of the plate 3 is a gear pinion 7, the shaft 8 of which is rotatably supported in the plate and provided on the rear side of the plate with a bevel pinion 9. Rotatably supported on opposite sides of the gear pinion 7 are driving gear pinions 10 and 11. These pinions 10 and 11 are rotatably supported in the plate 3 in the plane of the gear pinion 7 and are in mesh with the gear pinion 7.

Slides 12 overlie and bear on the guide bar 5 and have extensions 13 fitting within the channel 6 of the guide bar. The slides proper 12 and the extensions 13 which fit in the channel 6 are preferably made in separate parts and secured together in an appropriate manner. Between the slides proper 12 and the extensions 13 are secured throw plates 14 which extend upwardly and are provided with vertically extending slots 15 preferably throughout the full length of the throw plates upwardly from the slides.

The respective throw plates 14 are designed to be moved in the rotation of the driving gear pinions 10 and 11, and to provide for this movement, each driving gear pinion is provided with a pin 16 fitting in the slots 15 of the respective throw plates with the outer ends of the pins preferably enlarged or having a disk terminal 17 of a diameter exceeding the width of the slot to prevent relative separation of the throw plates and driving gear pinions.

Obviously, in the rotation of the gear pinion 7, the driving gear pinions are operated and the pins 16 will correspondingly move the throw plates. As the driving gear pinions 10 and 11 necessarily move in opposite directions, the disposition of the pins 16 at opposite diametric extremities of the respective drive pinions will obviously cause such pinions to move the throw plates in relatively opposite directions, that is toward each other and from each other, compelling a similar movement of the slides.

As the extent of movement will depend upon the distance at which the respective pins 16 are spaced from the centers of the driving pinions, and as it is obviously desirable to vary the throw in order to control the prismatic power used in treatment, each driving gear pinion is provided with a series of openings 18 radially aligned from the center in one direction, so that the pin 16 may be positioned in a selected opening 18 to secure the necessary limit of movement of the slides in accordance with the particular treatment desired.

Slidably mounted on each slide plate 12 is a clip 19, the edges of which slidably embrace the upper and lower edges of the slides 12, with the main body of the clip overlying the front of the slides and provided with a set-screw 20 by which the clip may be fixed in any desired position longitudinally of the slide. The spherical lenses 21 are secured to the clips 19 depending therefrom so as to register at all times with the openings 4 in the plate 3.

As the lenses 21 are ordinarily the lenses employed by the particular person for reading purposes, it is quite apparent that when the apparatus is in place on the head of the patient, the lenses are in position to serve their usual function for reading or other purposes and that with the pinion 7 in motion, these lenses are moved toward and from each other in order that the prismatic effect or influence on the vision may be varied from the normal optical point of the lens.

In order to provide for appropriate movement of the pinion 7, the shaft 22 is rotatably supported on the rear surface of the plate 3, terminating at its inner end in a bevel pinion 23 in driving cooperation with the bevel pinion 9 and extending outwardly beyond one edge of the plate 3 and there provided through a universal joint 24 for driving connection with an extensible member 25, the end of which, remote from the shaft 22, is connected through a universal joint 26 with the

drive shaft of a motor 27. The motor 27 is supported upon a pedestal 28 having a weighted base 29 and made up of telescopic sections 30 to determine height, with the sections held in adjusted position by a set-screw 31. The motor may be 5 and preferably is supported directly upon a wooden block 32 mounted upon a rubber section 33 carried by the upper end of the telescopic member of the pedestal.

The extension member 25 is made up of spaced 10 rods 34 having a central rod 35, with one terminal connected through the universal joint 24 with the shaft 22 and the other terminal having an end piece 36 slidably embracing the spaced rods 34. Thus, the extensible member is freely movable in 15 any direction through the universal joints and freely extensible to permit comparatively free movement of the head of the patient within limits to avoid interference with the natural movement during reading or other uses of the glasses 20 while maintaining the treatment.

The revolution of the pinion 7, and therefore the revolution of the driving pinions 10 and 11, which are of the same diameter as the pinion 7, is very slow, comparatively speaking, moving 25 from three to approximately twelve revolutions per minute. This causes a comparatively slow change in the positions of the spherical lenses, so that the variation in prism power incident to such change in position of the lenses does not 30 seriously interfere with the comfort of the patient or his use of the lenses for ordinary purposes during the treatment.

The primary purpose of the method and apparatus is to build a new and comfortable reflex 35 action between the functions of sight, that is clearness and singleness of vision. Clearness of vision is controlled by the ciliary body including the muscles and nerves inside the eye-ball and singleness of vision is controlled by the extra-ocular muscles outside the eyeball. There must be a reflex action between the functions to bring about clearness and singleness of vision at one 40 and the same time. This reflex action becomes very fixed in association between the two functions and when lenses are placed before the eyes, there is required an alternation in the reflex action to meet the requirements of each function.

If plus lenses are placed before the eyes, they inhibit a given amount of stimulation that has been flowing for clearness of vision so naturally through the reflex action singleness of vision would be less stimulated and vision would be doubled. Immediately the brain, which is in control of all nervous energy, attempts to set up a 55 new reflex action between the two functions but in those cases where this is not secured, that is the alteration in the reflex action is not successful, outside assistance to secure the result has to be provided.

Through the apparatus and method described, the lenses are brought closer together and moved farther apart alternately. Thus, when plus lenses are used, the closer together the lenses may be, the greater the base in prism power, giving rest to singleness of vision, but the farther separated the lenses are, the greater the stimulus to singleness of vision. When minus lenses are used, the closer together such lenses may be, the greater the stimulus to singleness of vision and the farther separated the lenses may be, the greater the rest effect.

In the modification shown in Figures 8 to 11, inclusive, the instrument includes a head band 37, similar to the head band of the preferred 75

form, on which is removably secured a casing 38, preferably cylindrical. The casing is divided by a transverse partition 39 into a rear chamber 40 and a forward chamber 41, the latter being preferably of shallow depth and the former being of a depth to appropriately receive a motor 42 of a type designed to carry out the function of the apparatus. The motor is conventional, forms no part of the present invention and needs no further detailed description.

The motor shaft 43 extends through and is mounted in the partition 39 and carries a gear wheel 44 immediately in advance of the partition 39. This gear wheel 44 cooperates with gear pinions 45 and 46 of identical diameter and rotatably supported in the partition 39 below the gear 44. Secured to the outside of the casing 38 in vertical line with the partition 39 is a transversely extending plate 47 which, as shown in Figure 10, is of angle form.

Slidably supported on the plate 47 are slides 48 and 49, which slides, while mounted for sliding cooperation with the plate 47, extend below the plate and are interiorly formed with threads 50 which cooperate with an adjusting rod 51 having oppositely threaded portions 52 and 53 and provided immediately beyond the ends of the plate 47 with knurled projections 54 through the medium of which the rod 51 may be turned at will and the slides 48 and 49 caused to move toward or from each other in accordance with the direction of rotation of the adjusting rod.

The respective slides 48 and 49 carry fixed angle supports, indicated at 55 and 56, which supports depend from the slides and are then projected outwardly relative to each other in substantial parallelism with the plate 47. The free terminals of the supports 55 and 56 carry pins 57 on which are rotatably supported sleeves 58. The pins 57 extend in parallelism with the axis of the casing 48, are disposed below the casing and project inwardly toward the head band 37.

Fixed to the inner ends of the sleeves 58 are socket extensions 59 in which are slidably supported bars 60 carrying appropriate lenses 61. The outer end of each of the sleeves 58 is rigidly connected to one end of an angle lever 62, the opposite end of which angle lever is connected through a link 63 with a pin 64 eccentrically connected to the respective pinions 45 and 46. The eccentric connection of the respective links 63 is, of course, in diametric opposite relation with respect to the two pinions and to provide for adjustable throw, the pinions 45 and 46 are provided with a series of radially aligned openings 65 for receiving the pin 64.

The motor is energized conventionally through flexible conductors 66 designed to be connected to any convenient outlet box. While the motor is operating, the angle levers, through the links 63, rotarily reciprocate the sleeves 58 and move the lenses 61 slowly toward and from each other in a slightly arcuate path to secure the desired result. The lenses may be adjusted relative to each other in order that the lenses may be adjusted to accommodate the eyes of the patient both in the normal use of the lenses and during treatment.

In the form of the invention shown in Figures 8 to 11, inclusive, as well as in the preferred form, the apparatus as a whole is designed to be worn by the patient and the lenses used in ordinary reading purposes during treatment. Of course, the conductor 66 is of such a length to

allow the patient perfect freedom, within limits, while wearing the instrument.

Through the shifting of the lenses provided, an increased play or tolerance between the functions of stimulation and relaxation is created, allowing for a greater tolerance of the two functions, that is clearness and singleness, to act in accordance with one another while at the same time maintaining enough play between the functions to insure comfort and clear and single vision.

Of course, the invention contemplates, if necessary in a particular case, the use of an appropriate spherical lens or the use of any combination of spherical and cylinder lenses according to the needs of the particular patient. Stronger lenses 15 may be used if necessary and the throw of the lenses may be increased or decreased according to the requirements of the particular patient in maintaining the functions of clearness and singleness of vision created during such adjustments.

The instrument as a whole is used for treatment while the lenses are being used by the patient in reading or other ordinary purposes. Thus, under the direction of the optometrist, the treatments may be taken at home during the time the patient ordinarily employs in reading and, therefore, no particular loss of time on the part of the patient is occasioned for the treatment, such, for example, as would be the case 30 where the patient was compelled to visit the office of the optometrist by special engagement.

Furthermore, the apparatus as a whole is so simple and inexpensive as compared with instruments for similar treatments, that the optometrist 35 may readily have a number of such instruments and thus treat a number of patients at the same time without discomfort to the patient and while permitting him to employ the time of treatment in reading, for example.

It is, of course, to be understood that the present apparatus is designed for the handling of spherical lenses employed for reading and like purposes and thus to be clearly and carefully distinguished from testing lenses which are only employed for the purpose of testing the eyes to determine what spherical lenses will be later constructed for use. Therefore, in the following claims, the term "ordinary" is intended to mean those lenses which would ordinarily be employed 40 in eyeglass frames for the use of the particular person in reading, and to this extent the inclusion of the term "ordinary" in the claims is intended to limit the type of lenses with which the construction and operation defined in the claims is 45 particularly concerned.

What is claimed to be new is:

1. A method of exercising the eyes through and during the use of the ordinary reading lenses and without in any way interfering with the reading 60 function of such lenses, consisting in mounting the lenses on the head of the user in a position to permit the usual reading function, adjusting the lenses relative to each other to insure maximum prismatic effect for reading purposes, and then constantly and uninterruptedly moving the lenses to gradually and constantly decrease and increase the prismatic effect of the lenses while at all times maintaining the lenses in that position relative to the eyes of the user as will permit the 65 reading function, the exercising movement being such as to avoid interference with the reading function of the lenses during such movement.

2. A method of exercising the eyes through the use of the ordinary reading lenses and without in- 75

terfering with such reading function during the exercising movement, consisting in mounting lenses on the head of the user to permit ordinary and usual reading function through such lenses, and then constantly and uninterruptedly moving the lenses to vary the prismatic effect of such lenses for exercising the eyes, the exercising movement being continuous and being limited in degree to avoid interfering with or preventing the reading function of the lenses during such exercising movement.

3. A method of exercising the eyes, consisting in mounting lenses peculiarly adapted to the user for conventional reading purposes to permit the ordinary reading function of such lenses, and then moving the lenses constantly to and from a position of normal reading function to vary the prismatic effect of the lenses on the eyes of the user for exercising the eyes, the complete exercising movement being such as to vary the prismatic effect of the lenses to a degree to avoid complete interruption of the reading function of the lenses at any time during the exercising period.

25 4. A means for exercising the eyes, including

a mounting, lenses having the necessary characteristics to provide an ordinary reading function for the user, slides supporting the lenses, throw bars connected to the slides, and means for selectively operating the throw bars to automatically and continuously move the slides and thereby the lenses to vary the prism effect of the lenses for exercising purposes, the maximum limit of the throw bars being such as to avoid any movement of the lenses during the exercising function which will interfere with the reading function of the lenses.

5 5. A construction as described in claim 4, wherein the throw bars are moved in opposite directions during the exercising function.

6. A construction as described in claim 4, 15 wherein the lenses are adjustably connected to the slides.

7. A construction as defined in claim 4, wherein the means for moving the throw bars includes a power driven pinion, drive pinions intermeshing with the power driven pinion, and connections between the drive pinions and throw bars.

CHARLES H. SCHWANER.
